UNITED STATES PATENT OFFICE.

WILLIAM O. GILBERT, OF ARROWSMITH, ILLINOIS.

ADJUSTABLE BRACKET.

1,142,694.

Specification of Letters Patent. Patented June 8, 1915.

Application filed May 9, 1912. Serial No. 696,266.

To all whom it may concern:

Be it known that I, WILLIAM O. GILBERT, a citizen of the United States, residing at Arrowsmith, in the county of McLean and State of Illinois, have invented certain new and useful Improvements in Adjustable Brackets; and I do hereby declare the following to be a full, clear, and exact description of the invention, such as will enable others skilled in the art to which it appertains to make and use the same.

This invention is an adjustable bracket adapted more particularly for use upon inclined roofs, the objects of the invention being, first, to firmly support a staging at various distances from the apex of the roof for the purpose of constructing or repairing chimneys, or the like, at the apex of the roof or at points intermediate of the apex and the eaves thereof; second, to support the stage in a substantially horizontal position irrespective of the slant of the roof, and, third, to provide a bracket for general use which is of simple and inexpensive construction, the parts of which may be retained in unyielding operative position, and which may be packed into a small space to facilitate transportation.

The bracket comprises a base member, parallel upright members pivotally secured near one end to the base member, said parallel upright members being trussed to retain them in rigid upright position, a weight-carrying member, pivotally connected to the base member, having means for adjustably mounting the same between the upright members, and means for retaining the bracket upon a roof.

In the accompanying drawings, forming a part of this application, I have illustrated one embodiment of the invention, but the construction shown therein is to be understood as illustrative only, and not as defining the limits of the invention.

Figure 1 is a perspective view of the bracket applied to a roof. Fig. 2 is a side elevation of the bracket with the extension member removed. Fig. 3 is a plan view of the bracket folded into compact position. Fig. 4 is a detail view of the extension member.

The brackets of this invention are preferably arranged in pairs, which operate to support a platform. Each bracket is provided with a base member, a weight-carrying member pivoted to the base member,

and an upright member preferably arranged in pairs, provided with means coöperating with the weight-carrying member and the base member for supporting the weight-carrying member in a substantially horizontal position. The base member is provided with an extension member which may be united to the bracket for the purpose of positioning the bracket at various places below the apex of the roof. The upright member is preferably trussed and it is so united to the other members of the bracket as to preclude yielding movement of the upright member relative to the base member.

In the embodiment of the invention illustrated in the accompanying drawings, the base member is composed preferably of two parallel bars 5, provided with a plurality of oppositely positioned holes 6.

Hooks 7 preferably in the form of angle irons are removably secured, as by bolts 8, to form a rigid connection with the base member.

A weight-carrying member 9 is pivotally secured at 10 to this base member 5, said weight-carrying member being preferably positioned between the parallel bars 5 of the base member in order to facilitate the folding of the parts of the bracket into a small space for transportation and the like. When the weight-carrying member is folded between the base members, it rests upon the plate *a* of said base member. This weight-carrying member 9 may be of any suitable material, but to reduce the weight, cost of manufacture, and at the same time retain the strength of the parts, I prefer to make the member 9 of a plurality of parallel strips of wood which are separated by a metallic plate or strip 11 extending the full length of the weight-carrying member, said parallel strips 9 and metallic plate 11 being bolted or otherwise secured together. This member is provided, also, with a plurality of transverse holes 12 which register with some of the holes 6 within the base member and through which holes 6, 12, a bolt or other fastening means may be passed to retain the parts in a folded position.

The member 9 is provided, also, with a plurality of transverse holes 12 which register with some of the holes 6 within the base member and through which holes 6, 12, a bolt or other fastening means may be passed to retain the parts in a folded position. The under surface of this base member is provided with a plurality of transverse grooves 13, the purpose for which will be hereinafter set forth.

The upright member is preferably composed of two parallel bars 14, each of which is provided with a plurality of holes or

apertures 15, the holes of one bar being arranged opposite to those of the other bar for the purpose of receiving a bolt 16. This bolt is adapted to be positioned at various places on the upright part to correspond to the slant of the roof.

The bolt 16 coöperates with the transverse grooves 13 of the weight-carrying member to permit one end of said member to rest upon the bolts 16 and be freely movable in a vertical direction between the upright bars 14, the bolt operating to preclude longitudinal movement of the bar when said bolt engages one of the grooves 13. The parallel bars 14 are preferably so positioned that the base member 5 and the weight-carrying member 9 may be compactly folded between the bars 14 of the upright member, as illustrated in Fig. 3.

To insure rigidity of the bracket and especially the upright member thereof, I have provided the parallel bars 14 with a base 17, a top brace 18, and have trussed the bars as at 19. The base 17 and the lower part of the truss coöperate to form a stop to limit the movement of the upright member in one direction and serve also as a rest to support the bars 14 in a vertical position. The base 17 is preferably curved, as at 20, to facilitate the movement of the upright member in a direction to fold the various parts of the bracket, the base 17 of said upright member operating to sustain the entire weight of the bracket during the operation of folding parts to the position shown in Fig. 3.

The extension member, which coöperates with the base member 5, is composed of a plurality of parallel sections 21, 22, each section being provided with a series of adjusting holes 23 and with bolts 24, 25 at each end of the sections. The space between the inner sections 21 of this extension member is substantially the same as the space between the parallel upright bars 14, thereby permitting the inner sections 21 to be positioned on each side of the base member 5, where they may be retained in transverse alignment with said members by bolts passing through holes 23 of the sections 21, 22, and through holes 6 of the base member 5. The unconfined ends of sections 22 may be provided with retaining hooks 7. If it is desired to position the bracket a considerable distance from the apex of the roof, bolt 24 may be removed, permitting these ends of the sections 21 to be secured to the end of the base member 5.

In operation, I preferably employ a pair of these brackets spaced a suitable distance apart with a staging or platform resting upon the weight-carrying members 9, as shown in Fig. 1.

When it is necessary to repair a chimney situated on an inclined roof at a considerable distance from the apex thereof, the ex-

tension sections 21, 22 are bolted end to end by bolt 24, the hooks 7 of section 22 engaging the top of the roof at several points, shown in the drawings as at four points, said hooks operating to preclude movement of the bracket with reference to the roof. Bolt 16 is moved on the upright member to a position substantially on a horizontal plane with the bolt 10 of the base 7, to upright member resting on its base in a vertical position, and weight-carrying member 9 is then moved between the parallel bars 14 of the upright member until a groove 13 of said weight-carrying member engages bolt 16, thereby retaining the parts in operative position. The staging or platform may now be placed upon the weight-carrying members 9.

In transporting the device, bolt 16 is removed from the upright member thereby permitting the weight-carrying member 9 to fall into position between the bars 5 of the base member; bolt 16 is then inserted through one of the series of holes 15 in the upright bars 14, through the holes 6 of the base member and the holes 12 of the weight-carrying member, thereby retaining all the parts in a folded position in alignment with each other. If desired, the sections of the extension member may be so spaced apart that they may also be positioned in the same transverse plane as the other members of the bracket, the bolt 16 engaging the holes 24 of the extension member and operating to firmly secure all parts of the bracket and the extension member into compact form.

Having thus fully described my invention, what I claim as new and desire to secure by Letters Patent, is:—

1. An adjustable bracket comprising parallel base members, upright members pivoted to said base members, a weight carrying member pivotally mounted for free movement between said base members, a plurality of parallel extension arms, one pair of which are pivotally secured to said base members by a bolt which serves as a pivot for said weight-carrying member, and removable angular hooks secured to the free ends of said parallel extension arms, for the purposes specified.

2. An adjustable bracket comprising spaced base members having a stop plate on the lower face thereof, a weight carrying member pivotally mounted at one end and between said base members, spaced upright members mounted externally of the base members and pivotally connected to the latter at one end thereof, said upright members being trussed and braced on one face thereof and opposite to the stop plates of the base members, a removable bolt to pivotally connect one end of the weight carrying member to the base members, whereby the parts may be moved and retained in their weight sup-

porting position, or folded into compact form, and when so folded the unconfined end of the weight carrying member will be positioned between the trussed section of the upper right members and the stop plate of the base members, and means to lock the various members in a compact form.

In testimony whereof, I affix my signature, in presence of two witnesses.

WILLIAM O. GILBERT.
